UNITED STATES PATENT OFFICE.

JOHN B. EHRLICH, OF INDIANAPOLIS, INDIANA.

HOT-BLAST FOR RANGES OR COOKING-STOVES.

SPECIFICATION forming part of Letters Patent No. 701,474, dated June 3, 1902.

Application filed February 17, 1902. Serial No. 94,434. (No model.)

To all whom it may concern:

Be it known that I, JOHN B. EHRLICH, a citizen of the United States, residing at Indianapolis, in the county of Marion and State of 5 Indiana, have invented certain new and useful Improvements in Hot-Blasts for Ranges or Cooking-Stoves, of which the following is a specification.

The object of my invention is to provide a 10 hot-blast for ranges and cooking-stoves in which the air is procured at the top of the range or stove, conveying the same through a special constructed pipe which extends longitudinally into the fire-pot and discharging 15 the said air through slots in the pipe over the point of combustion, the object being to heat the said air before discharging and which is calculated to effect a more perfect ignition and combustion of the gases which arise from 20 the fire.

The object consists, further, in providing a pipe having an enlarged ingress-bowl formed integral therewith, and which bowl is secured to the top of the range or stove.

25 The object consists, further, in a discharge-pipe which is narrowest at its intersection with the ingress-bowl, the said pipe being semicircular in form and widens toward the front end. The discharge-pipe is closed at 30 the front end and is provided on the lower surface with a series of semicircular slots, through which the air is discharged. There are other features therein, and the construction and arrangement of the several parts 35 will be hereinafter more particularly described and then pointed out in the claims.

Referring to the accompanying drawings, which are made a part hereof, and on which similar numerals of reference indicate similar parts, Figure 1 is a fragmentary detail, in 40 plan view, of a range and shows the position occupied by my hot-blast. Fig. 2 is a vertical section of a range and shows my hot-blast in side elevation therein. In this figure I also show the means for connecting the 45 secondary ornamental ingress-bowl, which forms a stand for a swinging bracket. Fig. 3 is a fragmentary detail, in plan view, of a cooking-stove and shows the position occupied by my hot-blast. Fig. 4 is a vertical section through the stove and the hot-blast. Fig.

5 is a side elevation of the hot-blast, the range or stove being omitted. Fig. 6 is a bottom plan view of the hot-blast and shows the flaring of the discharge-pipe. Fig. 7 is a rear 55 elevation of my hot-blast and shows the manner in which the same is secured to the range or stove, and Fig. 8 is a cross-section of the discharge-pipe and shows the integral strengthening-rib in the bottom thereof.

60 In the drawings, 1 is the top of the range or stove, 2 the back, and 3 the fire-pot. The top 1 is provided at the rear and near the side edges with an elongated aperture, the contour of which corresponds with the ingress-bowl of my hot-blast. The top 1 in range construction extends considerably to the rear of the back 2, so that the apertures in the top are outside the said back.

4 is the discharge-pipe of the hot-blast, 70 which pipe terminates in an ingress-bowl 5. The pipe 4 is semicircular in form and widens horizontally as it advances toward the front end, and which construction provides the desired air capacity, besides saving more space 75 in a vertical manner than could be obtained in using a round pipe. The flat top of the pipe 4 allows the same to be positioned in close proximity to the range or stove top 1, and thus overcomes the objectionable feature in having the pipe mounted too low within the fire-pot. The pipe 4 is provided with a top plate 6, and which plate when it intersects the ingress-bowl 5 cuts to the center thereof, and thus brings the joint at that point which is 80 desirable. The top plate 6 and the pipe 4 are secured together by the bolts 7. The pipe 4 has an integral strengthening-rib 21 in the bottom, which adds stability to said pipe. 85 (See Fig. 8.)

90 The upper edge of the ingress-bowl 5 is flush with the surface of the range-top 1 when my hot-blast is in operating position. The ingress-bowl 5 has a damper secured in the upper end thereof, by which the ingoing air is 95 regulated. The damper is formed out of two slotted plates adjustably secured together and which are mounted in a horizontal manner in said bowl. The lower plate 9 of the damper is held in position between two annular flanges which are integral with the bowl. The plate 8 slides on the plate 9 and 100

carries a handle 20, by which the same is operated. The shifting of the plate 8 opens or closes the damper.

In the art of range construction it is customary to supply a range with brackets, which are usually hinged to the back that extends above the range-top. To provide brackets for my range, I mount the bowl 10, which is of any suitable design, to the top 1. The bowl in this instance forms the ingress to my hot-blast. The bowl 10 is provided with the integral ears 11, (see Fig. 1,) each of which carries an aperture. The ears 11 at the front of the bowl form a bearing for a swinging bracket 12, which may be changed to either of the said ears. The rear ears form a bearing for an ornamental back 13, and which back is a mere ornamentation for the range, the bowl 10, the bracket 12, and the back 13 being exposed to view and are highly polished. The stand 10 may be used in connection with a cooking-stove, if desired, but is most particularly adapted to ranges, since in a cooking-stove the fire-pot runs lateral therewith, and in which case the stand 10 would be an impediment.

The ingress-bowl 5 is provided on each side near the top with the horizontally-extended flanges 14, (see Fig. 7,) which flanges carry an aperture through which the bolts 15 pass and whereby the bowl is secured to the top 1. The pipe 4 is supplied with a flange 16, which is integral therewith, and which flange rests against the back 2 and is secured by the bolts 17. The pipe 4 from the flange 16 widens toward the front, and thus the channel in the pipe has a choke near the said flange. This is one of the main features of this invention, for as the air passes through the choked portion of the pipe it is immediately subjected to a heat of high degree, which causes the air to expand, and thus forms a suction in said pipe. Hence I am able to procure and discharge a greater volume of air into the fire-pot than would be possible were the pipe of a uniform diameter throughout its entire length. The pipe 4 is closed at the front end and is provided with a series of slots 18, which discharge and distribute the air. The slots 18 are cut on a circle, which is less liable to weaken the pipe than were the slots cut in a direct transverse manner.

Having thus fully described my said invention, what I desire to secure by Letters Patent is—

1. In a hot-blast for ranges and cooking-stoves, a discharge - pipe substantially as shown, the said pipe being semicircular in

form and terminating at one end in an integrally-formed ingress - bowl, slots in the 60 pipe which form an egress for the air, a plate 6 forming the top for the discharge-pipe, bolts passing through the top plate and the pipe by which the parts are secured together, integral flanges on the pipe and bowl which 65 carry apertures, bolts passing through the said apertures in the flanges and the range top and back, whereby a means is provided for securing the hot-blast to the range or stove, substantially as shown and described. 70

2. In a hot-blast for ranges and cooking-stoves, a discharge - pipe substantially as shown, the said pipe being semicircular in form and flaring in a horizontal direction, slots in the pipe which form an egress 75 for the air, the discharge - pipe extending through and is secured to the back of the range or stove by means of the flange 16 and the bolts 17, the discharge-pipe curving upward at its rear end and terminating in an 80 integrally-formed ingress - bowl, the upper edge of the bowl registering with an aperture in the range-top, flanges on the bowl which carry apertures for the bolts 15, annular integral flanges within the ingress-bowl which 85 form a seat for the damper-plate 8, a damper composed of the plates 8 and 9, the plate 9 of the damper being adjustably secured to the plate 8, the combined plates forming a means for regulating the inflow of air, substantially 90 as shown and for the purposes set forth.

3. In a hot-blast for ranges and cooking-stoves, a discharge-pipe semicircular in form, the said pipe extending into the firebox of the range or stove, the rear end of the pipe 95 being curved upward and terminating in an ingress - bowl, integral flanges on said bowl which carry apertures, bolts extending through the said apertures and the range-top, whereby the parts are secured together, a secondary ornamental stand secured to the upper surface of the range which forms the ingress for the hot-blast, ears integrally formed on the said stand, the front ears of which form a bearing for the swinging bracket while the 100 rear ears form a bearing for the ornamental back, substantially as shown and for the purposes set forth.

In witness whereof I have hereunto set my hand and seal, at Indianapolis, Indiana, this 110 3d day of February, A. D. 1902.

JOHN B. EHRLICH. [L. S.]
